BALL PUZZLE DEVICE

Filed April 6, 1929

UNITED STATES PATENT OFFICE

WILLIAM R. MAXWELL, OF BROOKLYN, NEW YORK, ASSIGNOR TO RIDA MAY EDGAR

BALL-PUZZLE DEVICE

Application filed April 6, 1929. Serial No. 353,023.

This invention relates to new and useful improvements in a ball puzzle.

The invention has for an object the provision of a device of the class mentioned which is of simple, durable construction, dependable in use and efficient in action, and which may be manufactured and sold at a reasonable cost. The invention proposes a ball puzzle device in which the object is to place buckshot into different openings in different portions of the device which is arranged to make such placement very difficult unless the system for producing the placement is known and then such placement is very simple.

The invention proposes a block of rectangular shape in plan view and having a curved bottom so that it may rock or may be spun around on its bottom, to have a hollow cut-out portion communicating with its top and the cut-out portion being curved at the bottom, small end apertures in the block communicate with the said hollow and located near the top of the block, and to have a transverse pin capable of separating a pair of buckshot placed in the hollow and viewable thru a transparent cover attached on the block. The device may be modified to assume the shape of a cross and then be provided with crossed pins and operate in the same fashion as the preferred form.

For further comprehension of the invention, and of the objects and advantages thereof, reference will be had to the following description and accompanying drawings, and to the appended claim in which the various novel features of the invention are more particularly set forth.

In the accompanying drawing forming a material part of this disclosure:—

Fig. 1 is a perspective view of a device constructed according to this invention.

Fig. 2 is a plan view thereof.

Fig. 3 is a longitudinal sectional view taken on the line 3—3 of Fig. 2.

Fig. 4 is a transverse sectional view taken on the line 4—4 of Fig. 3.

Fig. 5 is a plan view of the device constructed according to modified form.

Fig. 6 is a sectional view taken on the line 6—6 of Fig. 5.

Fig. 7 is an elevational view looking in the direction of the arrows 7—7 of Fig. 5.

The reference numeral 10 indicates generally a block of rectangular form in plan view and having a curved bottom 11, straight sides 12 and straight ends 13. A hollow 14 within the block has a curved bottom 15, straight sides 16, and communicates with the top of the block. End apertures 17 within the block near the top thereof communicate with the hollow 14. A transverse pin 18 engages within the block and near the bottom of the hollow 14.

A pair of buckshot 19 are disposed within the hollow 14 and may assume a position straddling the pin 18. A transparent cover 20 preferably of celluloid engages upon the top of the block and is held in a fixed position by pins 21.

The object of the puzzle is to get one of the buckshot 19 into one of the apertures 17 and the other into the other aperture. This is quite difficult to accomplish unless it is known that the complete block must be spun so that centrifugal force throws the buckshots outwards and into the apertures. In addition it is necessary to know that buckshot must initially be placed at opposite sides of the transverse pin 18 before spinning of the block so that they will be thrown in opposite directions and each enter the opposite aperture 17. The apertures 17 should be slightly inclined downwards so as to have a slight affinity for retaining the balls. If attempts are made to engage the balls into the apertures merely by positioning the block in different elevations or positions and tapping or slightly moving from these elevations or positions it will be found that as one ball engages in one of the apertures and the other tends to engage in the other the first will fall out of its first aperture.

In the modified form of the device illustrated in Figs. 5 to 7 inclusive, a block 10' has been shown which is of cross shape in plan view and has a substantially spherical bottom 11'. The sides of each of the cross

arms are straight as indicated by numerals 12' and the ends are also straight and indicated by numeral 13'. A crossed hollow 14' is formed within the block and has a substantially spherical bottom 15' and straight sides 16' at those portions where the hollow engages in the arms of the block. An aperture 17' is formed in each of the arms of the cross near the top of the block and communicates with the hollow 14'. A pair of crossed pins 18' are adjustably mounted in the block which is formed with vertical slots 22 so that the cross pins may assume various elevated positions. Nuts 23 threadedly engage the ends of the pins and are arranged for being screwed onto the pins for holding the pins in any elevated position. Four buckshots indicated by reference numeral 19' are engaged within the hollow 14'. A transparent cover 20' rests upon the top of the block and is held in fixed position by pins 21'.

The principle of operation of this device is similar to the preferred form. It is necessary to slightly shake the block until each of the balls assumes a position in one of the four corners formed by the crossing pins. To provide such four corners it is necessary to move the pins into their lowered positions. The reason that the pins may be raised consists merely in throwing off the solver of the puzzle from the correct solution. After he encounters difficulty in causing the balls to enter into the apertures he will scheme that the raising or lowering of the cross pins have some useful function for causing the balls to enter and this will mislead him. After the balls have assumed positions in the corners as stated, the block is spun around very rapidly and the pin offers resistance to centrifugal force except in one direction, so that one of the balls enters each of the arms of the hollow and finally enters each of the apertures 17'.

While I have shown and described the preferred embodiment of my invention, it is to be understood that I do not limit myself to the precise construction herein disclosed and the right is reserved to all changes and modifications coming within the scope of the invention as defined in the appended claim.

Having thus described my invention, what I claim as new, and desire to secure by United States Letters Patent is:—

In a puzzle device, a cross shaped block having a curved bottom, said block having a curved central depression, each extension of said block having a curved upwardly inclined depression forming a continuation of said central depression and a horizontal recess, a plurality of loose balls adapted to fit into the horizontal recesses of the block extensions upon movement of the block, transverse pins crossing at the center of the cen-

tral depression, said pins being at an angle of 45° to the extensions of the block whereby the central depression is divided into four areas, one adjacent each extension, and means for adjusting the elevation of said pins.

In testimony whereof I have affixed my signature.

WILLIAM R. MAXWELL.
